TYPOGRAPHICAL COMPOSING MACHINE

Francis J. Lynch, Great Neck, N. Y.

Application January 28, 1931, Serial No. 511,785
Renewed October 14, 1936

8 Claims. (Cl. 199—43)

My invention relates to improvements in typographical composing machines and more particularly to signaling devices for use with such machines. As is well known in the art of typographical composing machines, a distributor mechanism is employed to return the matrices to the magazines. The usual distributor mechanism comprises rotatable distributor shafts each provided with a screw thread for moving the matrices longitudinally of the shafts to distribute the same to their respective places in the magazines where they are stored until used again. The distributor shafts are connected directly or indirectly by means of a clutch to a suitable source of power which serves to rotate the shafts during normal operation of the mechanism. Due to various causes, such as worn or bent matrices, stoppages in said mechanism are of more or less frequent occurrence. The clutch then operates automatically to disconnect the distributor shafts from the source of power. In order to overcome or minimize difficulties due to stoppage of the mechanism, my invention embodies elements preferably adapted to be applied to existing typographical composing machines as of an attachment which includes any visible or audible signaling means which will serve to warn the operator or others of any stoppage in the distributor or any improper operation of the distributor mechanism preventing the return of the matrices to the magazines. My invention, while of simple construction, is adapted to withstand the shocks and strain of constant operation of the composing machine and can be attached to and adapted to use with any of the well known standard typographical composing machines.

It should be kept in mind that under business conditions today it is by no means unusual in large establishments to have as many as fifty or more composing machines in operation simultaneously. In such plants the machines are usually arranged in a row with an aisle at the rear or in double rows, back to back, with an aisle between them. When a stoppage occurs the distributor mechanism must be cleared from the rear of the machine and this would ordinarily require the operator to leave his position at the keyboard which is at the front of the machine. In large establishments this would result in frequent moving about of many operators with consequent unnecessary loss of time since it often happens that stoppages occur on a number of the machines at or about the same time. It is customary, therefore, in large composing rooms to have one person stationed in the aisle on the

alert for stoppages and he, of course, is in a convenient position to proceed to the rear of any machine to rectify any trouble such as a stoppage in the distributor mechanism. It will be seen, therefore, that my invention is an improvement over any method now in use, since it provides an instantaneous signal, the use of which increases the efficiency of operation of composing rooms through the elimination of unnecessary movements by a multiplicity of operators and reduces to a minimum the time during which the machines would ordinarily be out of operation.

Although my invention may be embodied in apparatus of any suitable form or construction, my invention as hereinafter described and as illustrated in the drawing represents a preferred form thereof adapted to be attached to existing typographical composing machines and comprises a bridge-like structure or member which is mounted adjacent the distributor clutch, the said member being provided with means for opening and closing an electric circuit upon movement of the distributor clutch of the composing machine as hereinafter described. An electric lamp, supported by a standard, is mounted on the bridge member and is lighted by the opening or closing of the electric circuit, thereby providing a signal to the operator and to the mechanic whose duty it is to clear such stoppages.

In the accompanying drawing:

Fig. 1 is an elevation of the device as viewed from the front of the composing machine;

Fig. 2 is an elevation showing the device as viewed from the right hand side of the composing machine; and

Fig. 3 is a side elevation showing the spring mechanism illustrated in Fig. 1.

The bridge structure or member of the form of apparatus illustrated in the drawing may be of any suitable material but is preferably of metal and comprises an inverted U-shaped member having a leg 1, a longer leg 2 and a cross bar 3. A standard 4 is arranged on the cross bar 3 and serves to support any signaling means, such as a lamp 5.

The lower end of the leg 1 is provided with an opening 6 shaped to conform to a bolt 7 so that when the inverted U-shaped member is in position on the composing machine it rests on said bolt and is removably clamped thereon by means of a nut 8 at the rear of said machine.

The lower end of the leg 2 is provided with an inwardly extending shoulder 9, the extremity of which is formed with an inwardly curved surface

10 adapted to snugly engage with the distributor clutch 11 as hereinafter described. When the inverted U-shaped member is secured in position on the composing machine in the manner previously described the leg 2 is arranged at the front of said machine, the curved surface 10 engages the surface of the distributor clutch 11 and the shoulder 9 is adjacent a collar 12 which is held in position on said distributor clutch by a cap 13. 10 It will be seen that the shoulder 9, by means of the curved surface 10, aids in maintaining the inverted U-shaped member in its operative position.

A lever rod 14, preferably of metal, is movably affixed, as at 15, to one side of the leg 2 and extends upwardly for substantially the entire length of said leg. The lower end of the lever rod 14 is shaped to form an arm 16 arranged substantially at right angles to said rod. The arm 16 is 20 so arranged with respect to the shoulder 9 that said arm will project slightly beyond said shoulder, and a coiled spring 17 attached at one end to the arm 16 and at its other end to the leg 2 serves to maintain said arm in its projected position while the distributor is returning the matrices to the magazines.

The leg 2 is provided with a slot 18 adjacent its upper end through which projects an arm 19 formed on the upper extremity of the lever rod 14, said arm being adapted to actuate a mercury switch 20 as hereinafter described. The function of the mercury switch is to make or break the electric circuit in a manner well known in the art of making and breaking such circuits, so as 30 to control the flow of current from its source to the lamp 5 or to any other signaling means which may be employed. The electric current to said signaling means is supplied through a circuit having a plug connection of the usual type. In 40 the present arrangement the circuit is broken at all times except when completed by the action of the mercury switch 20 which forms part of said circuit as hereinafter described.

The mercury switch 20, of known construction, 45 is supported by a T-shaped member 21, and is removably secured thereto by any convenient means such as the brackets 22. As illustrated in the drawing the switch is arranged with the end at which the circuit is completed or broken adjacent 50 the leg 2. The T-shaped member 21 is suspended from the cross bar 3 by a yoke 23 which is provided with a removable cross member 24 on which the T-shaped member 21 is mounted and which serves as a fulcrum for the movement of the member 21 and the mercury switch thereon.

The head 25 of the T-shaped member 21 projects toward the slot 18 to provide a seat on which the arm 19 rests at all times. The head 25 inclines upwardly from left to right, viewed from 60 the front of the composing machine, and while the distributor mechanism is functioning properly and the matrices are being returned to the magazines the arm 19 rests on the left or lower extremity of the head 25.

65 The circuit comprises a source of current furnishing electricity to the conductor 26 which is attached to one side of the mercury switch 20. When the switch is closed passage of the current is permitted through the conductor 27 to the lamp 5 and back through the conductor 28 to the source of current.

Upon the occurrence of a stoppage in the distributor mechanism, or when the distributor shafts cease to rotate for any reason, the clutch 70 automatically moves inwardly and brings the col-

lar 12 into contact with the end of the arm 16. This contact is sufficient to depress the end of said arm, the downward movement of which causes the rod 14 to move from left to right on its axis 15. Coacting with the rod 14, the arm 19 5 moves to the right or higher extremity of the head 25 of the T-shaped member 21, thereby depressing said head and elevating the opposite end of the mercury switch 20 which is mounted on the member 21. The mercury in said switch thereupon flows downward and completes the electric circuit, causing the lamp 5 to light.

The stoppage in the distributor mechanism is then cleared, the clutch readjusted to its operable position and the operation of the composing 15 machine is resumed.

It is to be understood that the invention is not to be considered as limited to the preferred form as described herein and as shown in the accompanying drawing, as any modifications thereof 20 may be accomplished without departing from the scope of the appended claims.

The expressions "abnormal movement of said clutch", and "abnormal stoppage of rotation" as used in the claims are intended to refer to movement of the clutch and stoppage of the distributor shafts which may take place as a result of improper operation of the machine due to displacement of a matrix or other faulty operation resulting in resistance to rotation of the distributor 30 shafts.

I claim:

1. In a typographical composing machine, a U-shaped member including an electrically operated signaling device, an electric circuit, a switch controlling flow of current through said circuit to said signaling device, and a lever mounted on said U-shaped member and automatically controlled by the distributor mechanism of the machine to open or close said switch. 40

2. In a typographical composing machine, a U-shaped member including a signaling device, an electric circuit, a switch member controlling flow of current through said circuit to said signaling device and a lever mounted on said U- 45 shaped member and adapted to be operated by the clutch mechanism of the machine to open or close said switch member and thereby operate said signaling device.

3. In combination, a typographical composing 50 machine, an electrically operated signalling device, an electric circuit, a switch controlling the flow of current through said circuit to said signalling device, a distributor mechanism, a clutch mechanism including an element movable in response to abnormally increased resistance in the distributor mechanism, and means between the clutch mechanism and the switch and operable by said element in unison with disengaging movement of the clutch upon stoppage of the distributor mechanism to close the switch and complete the circuit through said signalling device. 60

4. The combination with a typographical composing machine of an electrically operated signaling device comprising a signal, an electric 65 circuit, a switch controlling flow of current through said circuit to said signal, a collar mounted on and operated by the distributor clutch of said machine, and a lever rod mounted on said device and adapted at one end to operate 70 said switch upon being engaged at its other end by said collar.

5. A typographical composing machine having a distributor mechanism including a clutch mechanism with an element movable upon abnormally 75

- increased resistance in the distributor mechanism, a member, a signalling device, an electric circuit, a switch controlling the flow of current through said circuit to said signalling device, and
5 means mounted on said member and operable by the disengaging movement of said clutch in response to abnormal stoppage of the distributor mechanism to actuate said switch and thereby operate the signalling device.
- 10 6. A typographical composing machine having a distributor mechanism including a clutch mechanism with an element movable upon abnormally increased resistance in the distributor mechanism, a member, a signalling device, an electric circuit, a switch controlling the flow of current through said circuit to said signalling device, and a pivotal element on said member and movable about its pivot by movement of said clutch upon disengagement thereof due to a stoppage in said distributor mechanism, to close said switch and thereby operate the signalling device.
- 15 7. In combination, a typographical composing machine having rotatable distributor shafts, a clutch mechanism with an element movable in response to abnormal resistance to rotation of the distributor shafts, an electric circuit, a signal controlled by said circuit, a normally open switch in said circuit, and means operable by 5 the disengaging movement of the clutch when the distributor shafts are subjected to abnormal resistance to close the switch and complete the circuit through said signal.
- 10 8. In a typographical composing machine having a distributor mechanism, including a clutch movable into disengagement in response to abnormal resistance in the distributor mechanism, an electrically operated signalling device, an electric circuit, a switch controlling the flow of current through said circuit to said signalling device, and a pivotal element operable upon the disengaging movement of said clutch to actuate said switch and thereby operate said signalling device upon a stoppage in said distributor mechanism. 15 20
